DESIGN FOR A GRATE FOR A GAS BURNER

John D. Coleman, Detroit, Mich., assignor to The Aviation Corporation, New York, N. Y., a corporation of Delaware

Application June 4, 1945, Serial No. 119,886

Term of patent 14 years

(Cl. D81—25)

To all whom it may concern:

Be it known that I, John D. Coleman, a citizen of the United States, residing at Detroit, in the county of Wayne and State of Michigan, have invented a new, original, and ornamental Design for a Grate for a Gas Burner, of which the following is a specification, reference being had to the accompanying drawing, forming a part thereof.

In the drawing:

Fig. 1 is a perspective of a grate for a gas burner showing my new design.

Fig. 2 is a side elevation thereof.

Fig. 3 is a section taken on line 3—3 of Fig. 1.

I claim:

The ornamental design for a grate for a gas burner, substantially as shown.

JOHN D. COLEMAN.
